(No Model.)

G. W. McKIM.

STAVE CUTTER.

No. 276,262.

Patented Apr. 24, 1883.

UNITED STATES PATENT OFFICE.

GEORGE W. MCKIM, OF MARTIN'S FERRY, ASSIGNOR OF ONE-HALF TO
CHARLES W. THORNGATE, OF FREEPORT, OHIO.

STAVE-CUTTER.

SPECIFICATION forming part of Letters Patent No. 276,262, dated April 24, 1883.

Application filed April 14, 1882. (No model.)

To all whom it may concern:

Be it known that I, GEO. W. MCKIM, a citizen of the United States, residing at Martin's Ferry, in the county of Belmont and State of Ohio, have invented certain new and useful Improvements in Stave-Cutters, of which the following is a specification, reference being had therein to the accompanying drawings.

My invention consists in certain improvements in the construction of stave-cutters, which will be fully understood by the following description and claims.

In the accompanying drawings, Figure 1 is a transverse section of my machine. Fig 2 is a side view of the same. Fig. 3 is a detached view.

Upon the frame A is a swinging basket, I, supported on radial arms having pivots or journal-bearings B. This basket carries the knife-bar D and knife C, and all of these may be rotated upward to a vertical point above the bearings, and then tilted over to rest on the breast-plate F, out of the way of the workman, and in a position easily accessible for adjusting the knife-bar, breast-plate, and shear-plate without climbing over the frame. My knife C is made very thin, and is curved to fit the arc in which the knife moves in cutting a stave. This thin and flexible knife is embedded in the knife-bar D, which extends nearly the whole width of the knife, leaving only the edge thereof free. By this construction, the knife, being thin, cuts more easily, and can be sharpened with less labor. The knife-bar is

made of cast-iron and inflexible. It is also 35 adjustable by means of slots d and set-screws d'. The breast-plate F supports the shear-plate H, which is vertically adjustable by means of slots f and set-screws G, so as to be kept down close to the knife when swung forward in its stroke. The stave-bolt is to be placed in the basket I in front of the knife, and as the basket, bolt, and knife are swung forward a stave is cut from the under side of the stave-bolt, and falls out of the machine below the knife-bar, when the knife returns for the next stroke.

Having thus described my invention, what I claim is—

In a stave-cutter, the swinging basket I, in 50 combination with the thin knife C, embedded in and supported or stiffened by the knife-bar D, as described, and the adjustable breast-plate F, having the adjustable shear-plate H thereon, said basket, knife, and knife-bar all 55 supported on the radial arms or pivots, and being capable of being raised to a vertical point above said pivots, and then turned or tilted over, so as to rest on the breast-plate, out of the way of the workman in adjusting 60 the knife-bar, breast-plate, and shear-plate, substantially as and for the purposes set forth.

In testimony whereof I affix my signature in presence of two witnesses.

GEORGE W. MCKIM.

Witnesses:

W. C. DUVALL,
DANIEL BREED.
